UNITED STATES PATENT OFFICE.

ORVILLE HIRAM ENSIGN, OF LOS ANGELES, CALIFORNIA.

CARBURETER.

1,064,628.

Specification of Letters Patent.

Patented June 10, 1913.

Application filed April 11, 1912. Serial No. 690,191.

To all whom it may concern:

Be it known that I, ORVILLE HIRAM ENSIGN, a citizen of the United States, residing at Los Angeles, in the county of Los Angeles and State of California, have discovered and invented new and useful Improvements in Carbureters, of which the following is a specification.

This invention relates to a certain discovery and invention described in my application for Letters-Patent filed Jan. 5, 1912, Serial No. 669672 in which a vortex is employed in carbureting liquid hydrocarbons, and to improvements thereon.

15 An object of this discovery and invention is to constantly produce under all loads and conditions a uniform combustible mixture of liquid hydrocarbon and air; and to construct a carbureter of a minimum number 20 of simple parts that may be employed to automatically produce the results desired, without need of adjustment of the parts that effect the mixture after the carbureter leaves the factory.

25 Another object is to provide means for closely adjusting the level of the liquid fuel in the supply chamber to very near the level of the top of the supply nozzle, this being essential to maintain a constant mixture under all loads and conditions with permanent mixture adjustment.

30 A further object of the invention is to provide a construction of carbureter whereby by the inlet, the outlet and the fuel connections may be easily shifted to any desired positions relative to each other around a common axis, so as to facilitate installation on different types of engines.

I apprehend that in order to produce an ideal fuel mixture for internal combustion engines it is necessary that the correct proportions of air and liquid be mixed in such a manner that throughout the mixture each atom of the hydrocarbon shall be brought into close proximity to the necessary atoms of oxygen so that when ignition occurs, the proper chemical union called combustion will take place without any oxygen or fuel remaining uncombined; the quantity of liquid vaporized should be regulated solely by the weight of the air with which it is mixed and that the air and liquid should be so mechanically intermixed that the mixture will be uniform throughout its mass. It is

therefore a principle of this invention that 55 the forces employed to make the mixture shall work in even and undisturbed relation with each other. I have discovered that this even and undisturbed inter-action of the air and liquid can be induced and maintained by introducing the liquid to the low pressure zone of a vortex body or in other words, a helical stream of air, and holding the air body circumferentially confined for a period sufficient to allow the liquid under 65 the action of centrifugal forces to permeate the body, and then withdrawing the mixture. In this way the centrifugal forces acting on the liquid particles tend in a direction transverse to the paths of the air particles and this results in separating the liquid particles by frictional contact with the air particles, so that an even and intimate mixture of the air and oil will be produced.

75 I regard this invention as pioneer in various respects, among which may be mentioned the use of a vortex to effect the mixing and the use of a Pitot tube, vortex and related parts to effect the regulation of the 80 liquid supply by the action of the air supply.

A further feature of improvement consists in maintaining the normal liquid level of the hydrocarbon supply just below the level of a supply nozzle orifice, the walls of 85 which are of minimized length and which orifice is in a thin plate forming the top of a wide bore supply nozzle so that the amount of liquid passing through the nozzle will be determined only by differences of air pressures and the action of gravity and will not be affected by siphon action.

90 The accompanying drawings illustrate the invention.

Figure 1 is a plan section on irregular 95 line x^1-x^1 , Fig. 2, of a carbureter constructed to carry out this invention. Fig. 2 is a vertical mid-section on line x^2 , Figs. 1, 3, 4 and 5. Fig. 3 is a broken elevation from the left of Figs. 1 and 2; dotted lines 100 indicating interior construction. Fig. 4 is a view from the rear of Fig. 3; parts being broken away to illustrate the valve action. Fig. 5 is a plan section through the vortex chamber and air inlet on line x^5 , Figs. 2, 3 and 6. Fig. 6 is a fragmental sectional elevation on irregular line x^6-x^6 , Figs. 1 and 5, showing the small shell like air inlet and

vortex carbureting chamber. Fig. 7 is an enlarged fragmental detached detail of the supply nozzle and the parts forming the passage between the supply and carbureting chambers.

5 The shell of the carbureter is practically formed of only three pieces, viz., the body *a*, outlet member *b* and cap *c*, held together by lower and upper bolts *d* and *e* and wing nuts *f*, *g*, the bolts *d*, *e* being hollow at their inner ends to form a nozzle chamber *h*, and screwed together inside the shell, and into a transverse partition *i* inside the shell which is mainly circular in cross-section and is divided by said partition into superposed supply and carbureting chambers *j*, *k* communication from one to the other being provided by inlet ports *m* from the supply chamber into the nozzle chamber *h*, and outlet ports *n* from the nozzle chamber *h* to the carbureting chamber *k*.

The lower bolt *d* is provided with a shoulder *p* and with hollow externally threaded portion *q* that is screwed through the partition *i* which is provided with a centrally arranged threaded orifice *r* for that purpose. The upper bolt *e* is hollow at its lower end and screws down upon the hollow threaded end portion *q*.

30 The supply nozzle 1 is provided with a flange 2 clamped on the threaded end *q* by the upper bolt *e*, and its upper end is a thin plate provided with a minute central supply orifice 3. The carbureting chamber *k* is provided with a tangential air inlet 4 into which is screwed and fitted a carefully-formed true contracted vein air inlet nozzle 5, thus constituting a snail-shell like air inlet and carbureting chamber having an axial downward outlet formed by the circular mixture outlet nozzle 6 formed in the outlet member *b* and communicating with the return bend 7 forming the mixture passage which may have a drain cock 8 and may be controlled by a butterfly valve 9 and may be fitted to a suitable connection 10 that may lead to an internal combustion engine or other vacuum producing or mixture receiving appliance, not shown.

55 The supply chamber is provided with a hollow projection 11 forming the supply valve chamber and the supply-way communicating with the supply chamber *j* in which is mounted the valve float 12 fastened by a screw 13 to a lever 14 that is journaled on an eccentric pin 15 in position to contact with the valve stem 16 working through a guide 17 to hold the valve 18 to close the valve seat 19 which is connected by suitable means as the union 20 with the fuel supply pipe 21. The guide 17 is seated in a slotted bushing 22 screwed into the floor of the hollow projection 11; the lower end of the guide being tapered and the upper end 65 of the bushing being slotted as at 23 to

allow the liquid to flow into the supply chamber when the valve is raised by the liquid in pipe 21.

The eccentric pin 15 which carries the valve lever 14 is mounted by its journal 24 in a bearing 25 formed in one of the walls of the valve chamber and is provided with means as the slot 26 by which it may be turned, to adjust the lever 14 to raise or lower the valve float 12 to determine the level at which the liquid in the chamber *j* will stand when the float 12 holds the valve 18 closed against the pressure of the liquid fuel in the pipe 21, such pressure being at all times sufficient to cause the unobstructed liquid to flow from the valve into the supply valve chamber 11 from which it will flow by gravity into the supply chamber. A set-screw 27 screwed against the journal holds the lever pin in its adjusted position.

85 A distributor 28 which is preferably conical and hollow at its lower end is mounted on the bolt *d* below the fuel port *n*, being preferably formed integral with the bolt; and its lower end terminates at about the level of the upper end of the outlet nozzle 6, there being an open space forming an annular passage 29 leading underneath the distributor to the mixture nozzle 6. The air inlet nozzle 5 is provided with a straight portion 30 arranged tangentially relative to the circular mixing chamber *k*, thus giving it a snail shell like form; and inside said straight portion 30 is provided the receiving end of a Pitot tube communicating 95 with the supply chamber *j* above the liquid level. Said Pitot tube may be formed by a small bent tube 31 and a bore 32 into which the tube is inserted; the bore being formed in the side wall of the chamber and terminating near the upper end thereof.

105 The bolts *d* and *e* are provided with wrench seats 33 by which they may be turned to screw them together in place; and when the parts are assembled, the wing nuts *f* and *g* or either may be loosened so as to allow the cap and the outlet end-piece or either to be rotated or to be removed as may be desirable. In this manner the air inlet nozzle 5 and the mixture outlet 10 may be 115 relatively shifted, thus adapting the carbureter for attachment to different kinds of engines.

120 The cap *c* may be provided with the usual priming device comprising a pin 34 working through a bushing 35 that is screwed into the top of the cap *c*; said pin being pressed upward by the spring 36 between the bushing and the head 37 of the pin; and the bell-crank lever 38 pivotally mounted by pin 39 125 on a bracket 40 held on the cap *c* by the bushing 35 may be operated in the usual manner by connection 41 to depress the pin, and consequently the float, thereby to raise the level of the liquid above the supply nozzle 130

zle orifice 3 for priming purposes. An annular drip cup 42 is formed around the mixture outlet nozzle 6 to receive the drip from the distributor 28, thus to hold liquid 5 fuel in position to be taken up by air sucked toward the nozzle 6 by the action of the engine, not shown, when starting.

In practice the carbureter being connected by the pipe 10 with an internal combustion 10 engine, not shown, and by the pipe 21 with a liquid fuel supply, not shown, having sufficient head to cause a flow of liquid past the valve 18 when the liquid level in the supply chamber *j* is below normal and the float 12 15 lowered, will be ready for action and the liquid will flow into the supply chamber and adjustment of the float may be had by turning the eccentric pin until the float will allow the engine pressure to open the valve 20 whenever the liquid level in the supply chamber sinks a fraction below the level of the top of the nozzle, so that any slight reduction of air pressure in the carbureting chamber below that in the supply chamber 25 will cause liquid to flow through the orifice.

The adjusting journal 24 may be turned to adjust the pin 15 so that the float will open and close the valve as the liquid level 30 fluctuates just below the level of the orifice 3. When suction is produced in the outlet passage 12, thus causing the air to flow through the inlet nozzle 5, the mixing chamber *k* and the mixture outlet nozzle 6, the body of air in the carbureting chamber will 35 be caused to rotate in the chamber in a helical stream, there being created by such suction a zone of low pressure at the bottom of the carbureting chamber, and by reason of 40 the centrifugal force within the rotating stream of air, a central zone of low pressure is induced at the center of the upper end of the carbureting chamber.

The difference between the pressure of the 45 upper low pressure zone and the air pressure on the surface of the liquid in the supply chamber causes the liquid in the nozzle chamber *h* to rise from the port *n* and flow over the end of the supply nozzle and 50 through the small circular orifice 3, whence it falls through the large nozzle bore 43 which is specially enlarged to avoid the action of capillary attraction between the orifice 3 and the port *n*, which may consist of 55 a plurality of perforations as shown in Fig. 5.

The fall of pressure in the upper low pressure zone below that in the mixing chamber is proportional to the weight and 60 square of the velocity of the air in the nozzle 5.

The pressure in the liquid supply chamber is a result of the pressure and velocity head of the inflowing air as applied by 65 means of the Pitot tube; the air in the nozzle

5 being formed as a carefully-tapered contracted vein funnel, eliminates, when open to quiet atmospheric air, the major portion of the losses due to entry head; and when so opened allows the vaporizer to function 70 well without the Pitot tube and with the supply chamber open to atmospheric air; so that the cap *c* may in some instances be removed without destroying the value of the vaporizer under quiescent atmospheric conditions. 75

The object of the Pitot tube is to eliminate entry head losses whatever they may be, to cause perfect working at all times, and to make it possible to connect the air nozzle 80 by means of pipes, not shown, to a supply of heated air for carbureting liquid fuels not easily carburized. Such heating of the air and the friction in the pipe mentioned will cause rarefaction of the air supplied 85 through air inlet nozzle 5; and the Pitot tube takes into account the varying weight of such air and thus adjusts the pressure in the supply chamber *j* with reference to the pressure in the carbureting chamber so as 90 to keep the difference of pressure across the orifice 3 always proportional to the weight and square of the velocity of the incoming air. Therefore the difference in pressure between the supply chamber and the center 95 of the top of the carbureting chamber is, regardless of the quantity or density of the air flowing, the proper pressure to cause liquid proportional to the weight of the supplied air, to flow through the orifice 3. 100 Consequently when the float has been adjusted to hold the liquid in the supply chamber at a determined level close to the top of the supply nozzle *h*, the proportions of 105 liquid and air which will be contained in the mixture flowing through the outlet nozzle 6 will remain constant under all conditions.

Under ordinary engine action the velocity of the air through the middle chamber 110 will be very great and since the liquid is delivered to the center or vortex of the revolving body of air and thereafter partakes of the high speed of such air, its specific gravity being greater than the air, gives 115 it a tendency to force its way outward and downward, at the same time its downward movement being comparatively slow to its rotary movement.

The lower end of the carbureting chamber 120 is contracted or drawn in, so that the body of air is gradually contracted to the space underneath the distributor. Care is taken, however, that such space shall not be of less cross-sectional area than that within 125 the outlet connection, so that there is no acceleration of the mixture greater than that in the air nozzle 5.

By removing one of the wing nuts the cap or the outlet member, as the case may be, 130

can be detached thus giving access to the supply chamber and the float valve or to the carbureting chamber; and by unscrewing the top bolt, access may be had to the nozzle which may be removed and replaced with another, not shown, having a different size orifice, thus to accommodate different kinds of fuel, if found necessary or desirable.

It is to be noted that the nozzle chamber 10 serves as means to seal the nozzle orifice 3 against the air pressure of the supply chamber and that the air pressure in the nozzle chamber is controlled by the vortex.

The mixture outlet nozzle 6 is extended 15 about the floor of the chamber so as to turn the rotating current upon itself as the mixture is emitted.

It is understood that the low pressure zones at top and bottom of the vortex carbureting chamber may be produced by 20 forcing air through the tangential air inlet into the circular chamber either by atmospheric pressure or by air pressure in excess of atmospheric pressure; and the nozzle 30 and engine connection 10 in the relation 25 shown to the circular chamber indicate the means for creating said low pressure zones.

I claim:

1. A carbureter comprising a body having 30 upper and lower terminal seats and between said seats a supply chamber, a snail shell like air inlet and carbureting chamber below the supply chamber and a centrally perforated partition between the supply chamber and carbureting chamber; an outlet 35 member fitting the lower seat of the body; a cap fitting the upper seat; a bolt threaded at both ends, one end of the bolt being hollow and screwed through the partition and 40 provided with a port opening into the carbureting chamber; the lower end of said bolt extending through the outlet member and provided with a nut to hold the outlet member in place; an upper bolt having a 45 hollow lower end screwed onto the upper end of the first bolt and provided with a port from the supply chamber to the interior of the bolt; the upper end of said upper bolt extending through the cap and provided 50 with a nut to engage the cap; the cavities of the two bolts forming a nozzle chamber; a nozzle mounted in said nozzle chamber and provided at the top with an orifice; and means to maintain a liquid level 55 in said supply and nozzle chambers just below the level of the top of the nozzle.

2. A carbureter comprising a body having upper and lower terminal seats and between said seats a supply chamber, a snail shell like air inlet and carbureting chamber below 60 the supply chamber and a centrally perforated partition between the supply chamber and carbureting chamber; an outlet member fitting the lower end of the body and rotatable thereon; a cap fitting the upper seat

a bolt threaded at both ends, one end of the bolt being hollow and screwed through the partition and provided with a port opening into the carbureting chamber; the lower end of said bolt extending through the outlet member and provided with a nut to hold the outlet member in place; an upper bolt having a hollow lower end screwed onto the upper end of the first bolt and provided with a port from the supply chamber to the interior of the bolt; the upper end of said upper bolt extending through the cap and provided with a nut to engage the cap; the cavities of the two bolts forming a nozzle chamber; a nozzle mounted in said nozzle chamber and provided at the top with an orifice; and means to maintain a liquid level in said supply nozzle chambers just below the level of the top of the nozzle.

3. A carbureter comprising a body having upper and lower terminal seats and between said seats a supply chamber, a snail shell like air inlet and carbureting chamber below the supply chamber and a centrally perforated partition between the supply chamber and carbureting chamber; an outlet member fitting the lower seat of the body; a cap fitting the upper seat; a bolt threaded at both ends, one end of the bolt being hollow and screwed through the partition and provided with a port opening into the carbureting chamber; the lower end of said bolt extending through the outlet member and provided with a nut to hold the outlet member in place; an upper bolt having a hollow lower end screwed onto the upper end of the first bolt and provided with a port from the supply chamber to the interior of the bolt; the upper end of said upper bolt extending through the cap and provided with a nut to engage the cap; the cavities of the two bolts forming a nozzle chamber; a nozzle mounted in said nozzle chamber and provided at the top with an orifice; and means to maintain a liquid level in said supply and nozzle chambers just below the level of the top of the nozzle; and a distributor in the carbureting chamber below the supply port.

4. A carbureter comprising a body having upper and lower terminal seats and between said seats a supply chamber, a snail shell like air inlet and carbureting chamber below the supply chamber and a centrally perforated partition between the supply chamber and carbureting chamber; an outlet member fitting the lower seat of the body; a cap fitting the upper seat; a bolt threaded at both ends, one end of the bolt being hollow and screwed through the partition and provided with a port opening into the carbureting chamber; a distributor on said bolt; the lower end of said bolt extending through the outlet member and provided with a nut to hold the outlet member in place; an upper bolt having a hollow lower

- end screwed onto the upper end of the first bolt and provided with a port from the supply chamber to the interior of the bolt; the upper end of said upper bolt extending 5 through the cap and provided with a nut to engage the cap; the cavities of the two bolts forming a nozzle chamber; a nozzle mounted in said nozzle chamber and provided at the top with an orifice; and means to maintain 10 a liquid level in said supply and nozzle chambers just below the level of the top of the nozzle.
5. A carbureter comprising a body having a supply chamber, a snail shell like air inlet 15 and carbureting chamber below the supply chamber and a centrally perforated partition between the supply chamber and carbureting chamber; an outlet member fitting the lower end of the body; a bolt screwed into 20 the partition and provided with a port opening into the carbureting chamber; a distributor on said bolt; the lower end of said bolt extending through the outlet member and provided with a nut to hold the outlet member 25 in place; and means to supply liquid to the port.
6. A carbureter comprising a body having upper and lower terminal seats and between said seats a supply chamber, a snail shell like air inlet and carbureting chamber below the supply chamber, and a centrally perforated partition between the supply chamber and carbureting chamber; an outlet member fitting the lower seat of the 30 body; a cap fitting the upper seat; a bolt threaded at both ends, one end of the bolt being hollow and screwed through the partition and provided with a passage opening into the carbureting chamber; the lower 35 40 end of said bolt extending through the outlet member and provided with a nut to hold the outlet member in place; an upper bolt having a hollow lower end screwed onto the upper end of the first bolt and provided
- with a port from the supply chamber to 45 the interior of the bolt; the upper end of said upper bolt extending through the cap and provided with a nut to engage the cap; the cavities of the two bolts forming a nozzle chamber; and a nozzle located in 50 such nozzle chamber and having a thin plate elevated above the supply chamber port and having a central perforation, and a large bore below such perforation.
7. A carbureter body provided with upper and lower terminal seats, a liquid supply chamber and a carbureting chamber between the seats; a partition between the supply and mixing chambers and an air inlet into the carbureting chamber; the lower 55 60 terminal seat being annular, and there being a port between the supply chamber and carbureting chamber; an outlet member fitting the lower seat and rotatable thereon; a bolt secured to the partition and provided with 65 a nut screwed on the bolt and engaging the outlet member to secure it to said circular seat.
8. The carbureter shell set forth comprising a body provided with a partition, with 70 open-ended chambers on opposite sides of the partition there being a liquid inlet into one chamber, an opening through the partition and an air inlet into the other chamber; a mixture outlet member on the end of the 75 second chamber; a bolt connecting the outlet member with the partition, a cap on the end of the first-named chamber; and a bolt connecting the cap with the first-mentioned bolt.
- In testimony whereof, I have hereunto set my hand at Los Angeles, California, this 6th day of April, 1912.
